[57] **CLAIM**

The ornamental design for a wall mountable microwave oven, as shown and described.

DESCRIPTION

FIG. 1 is a front elevational view of a wall mountable microwave oven showing our design;

FIG. 2 is a side elevational view thereof;

FIG. 3 is a top view thereof;

FIG. 4 is a bottom view thereof;

FIG. 5 is a back view thereof; and

FIG. 6 is a sectional view taken along line 6—6 of FIG. 1.

The side of the oven which is not shown is a mirror image of the side disclosed in FIG. 2.
